HYDRAULIC TRANSMITTER

Percival Edward Thomas, Worcester Park, England, assignor to Sterling Industries Limited, London, England

Application May 23, 1947, Serial No. 750,088
In Great Britain May 29, 1946

4 Claims. (Cl. 60—54.6)

1

This invention relates to transmitters for use in hydraulic transmission systems.

The main object of this invention is to provide an improved arrangement of transmitter which, when incorporated in an hydraulic transmission system, will enable that system to be charged or primed by operation of the transmitter itself.

A further object is to provide an improved transmitter which will enable the liquid in a transmission system to be maintained under pressure, despite loss which may occur due to leakage.

A still further object is to provide a transmitter which will enable the system in which it is fitted to be "bled" by operation of the transmitter itself.

According to the present invention there is provided an hydraulic transmitter which comprises a pump, the working chamber of which is connected to a transmission line and the movable pumping element of which has an opening connecting the working chamber with a liquid chamber having in it a displacer provided itself with an opening connecting the liquid chamber to a reservoir for liquid. The movable element of the pump is so spring connected to the displacer element that movement of the movable element on its transmission stroke tends to move the displacer with it into the liquid chamber to a limiting position; and the opening in the movable pumping element is controlled by a non-return valve arranged to close the opening when the movable element is moved on its transmission stroke, while the opening in the displacer is controlled by a non-return valve arranged to close the opening when the movable element is moved on its return stroke.

Where such a transmitter is incorporated in a transmission system including the familiar receiver which is biased as by a spring to a datum position, it is possible as is fully described hereinafter, to prime the system with liquid at a predetermined pressure by operations of the transmitter itself, the arrangement being such that this pressure is automatically maintained.

The invention is illustrated in the accompanying drawings, in which:

Figure 1 is a longitudinal sectional plan, taken on line I—I of Figure 2;

Figure 2 is a longitudinal sectional elevation;

Figure 3 is an end elevation looking in the direction of the arrow III of Figure 2, but showing a part in section; and

Figure 4 is a transverse section on the line IV—IV of Figure 2.

2

Referring to the drawings, 1 indicates a transmitter or pumping element or plunger, which is slideable in a cylinder 2 and has a blank pressure end 3 fitted with a non-return valve 4 to close discharge openings 4'. The transmitter 1 is fitted with a pin 5 extending at each end beyond the transmitter and through slots 6 formed in the wall of the cylinder 2 where the ends of the pin are fitted with rollers 7 to be engaged by bifurcated operating arms 8 secured to an operating rock-shaft 9.

Slidable on the transmitter 1 is a displacer 10 and both the transmitter plunger 1 and this displacer 10 are hollow and thus provide jointly a chamber 11 for pressure liquid; the displacer 10 is controlled by a spring 12 which urges the displacer on the transmitter 1 so as to tend to decrease the volume of the chamber 11.

The operating face of the pumping element 1 opens into a sub-chamber 13 having an outlet union 14 for connection to the transmission line 24.

This line extends in the usual way to a receiver which is to be controlled by the transmitter, such a receiver being diagrammatically shown in Figure 2 as comprising a cylinder 25 having slideable in it a plunger 26 urged by a spring 27 against the pressure transmitted through the line 24 by the transmitter plunger 1, this spring being of sufficient strength to overcome the action of the spring 12. The term "receiver" is employed as is usual in the art, to denote apparatus which is to be actuated, by operation of the transmitter, for the purpose of effecting some control: for example, by the displacement of the plunger 26.

The non-return valve 4 is disposed to close automatically when the pumping element 1 is moved on its transmission stroke, i. e. to the left as seen in Figure 1.

The displacer 10 is formed with openings 16, placing the chamber 11 in communication with a reservoir 17 formed by the casing 18 of the transmitter, the openings 16 being controlled by a non-return valve 15 disposed to close when the pumping plunger 1 moves on its return stroke under the action of the pressure in the transmission line 14.

The system incorporates in the usual manner a normally closed bleed valve by which the system can be freed from air. It is preferred to dispose the bleed valve at a point adjacent the transmitter so that it can be operated by the operator stationed at the transmitter: in the form shown in the drawings this is achieved by incorporating the bleed valve indicated at

20 as part of the transmitter, the valve terminating a bleed line 19 which extends as shown in Figure 2 from the remote part of the system, the valve 20 being freed for the bleeding operation or normally locked by a screw plug 21 as shown in Figure 3: the valve 20 when freed enables air and liquid to pass into the reservoir 17 having itself a closure plug 22 which forms a filler plug for the reservoir and which can be removed to allow the free escape of air through a passage 23 during the priming operation.

The parts are shown in Figures 1 and 2 in full lines in positions they would occupy in normal use when the system is primed: in this condition the chamber 11 as well as the sub-chamber 13 and the line 14 will be charged with liquid which however is not shown in the drawing: when however the system is empty or requires replenishment, the displacer 10 will be drawn by the spring 12 to the dotted line position shown in Figures 1 and 2, in which position the displacer 10 abuts the end of the cylinder 2.

Assuming the system to be empty, it can be primed with liquid by repeated operation of the plunger 1, it being assumed that the bleed valve 20 is opened. The system being empty, the displacer 10 will be drawn by the spring 12 against the end of the cylinder 2. The plunger 1 is shown in the drawing at the end of its return movement so that when it is moved forward (i. e. to the left as seen in Figure 1), liquid will be drawn into the chamber 11 which increases its volume, past the non-return valve 15 from the reservoir 17. When the plunger is returned (i. e. is moved to the right as seen in Figure 1), this liquid or at least some part of it will flow into the transmission line past the valve 4 which opens during this return movement. Repeated strokes of the plunger gradually fill the system, the liquid being trapped in the system by closing of the valve 4. Liquid is prevented from returning to the reservoir 17 by the valve 15 which opens only while the plunger 1 moves forward when the displacer 10 is held against forward movement and so creates a drop in pressure in the chamber 11 by the closing of the valve 4.

When it is judged that the transmission has been bled, the bleed valve 20 is closed in the usual manner leaving a column of liquid between the pressure face of the plunger 1 and the pressure face of the receiver 25—26—27.

By now continuing the pumping action of the plunger 1, the forward movement of the plunger will move the receiver against its bias but will still cause liquid to be drawn into the chamber 11 past the valve 15. On the return stroke, the pressure reaction of the receiver will be transmitted back through the liquid in the line and will hold the valve 4 closed; the liquid in the chamber 11 being trapped by the valve 15 will now operate to displace the displacer 10 against the action of its spring 12 up to a limit, depending on the value of the spring 12. Continued operation of the plunger 1 will now cause the plunger and the displacer 10 to move together as a unit resulting in normal transmission to the system and hence to the receiver.

The spring 12 of course, operates to hold the liquid in the chamber 11 under pressure so that should the pressure in the transmission line fall below it due to leakage for example, the displacer will be drawn on by the spring 75

12 to force liquid past the valve 4 to replenish loss. When the displacer 10 reaches the limit of its travel under the urge of the spring 12, then the chamber 11 will be recharged and the spring loaded to maintain the desired pressure in the transmission; the spring 12 would be chosen to hold the liquid under a pressure above atmospheric pressure so that not only would any loss by leakage be made good but also air is prevented from entering the system.

It will be clear that for the purpose of insuring that under all operating conditions the chamber 11 shall become charged with liquid it is essential that a limit be imposed on this movement of the displacer 10 and this is effected of course by arranging the left-hand end of the displacer 10 to abut in the limiting position against the right-hand end of the cylinder 2, this being the position of the parts shown in dotted lines in Figure 1. Without such a limit, it would be impossible to rely on the movement of the plunger 1 with respect to the displacer 10 which is necessary to insure that increase in volume of the chamber 11 which is essential to cause liquid to be drawn through the valve 15 into the chamber 11 during the stroke of the piston 1 to the left.

Summary of operation

Normally, the parts, with the exception of the valve 4, will be in the positions shown in Figures 1, 2 and 3, the bleed valve 20 being closed, and the fluid system comprising the chamber 11, the sub-chamber 13, the pipe 14, and the receiver space to the right of the plunger 26 being filled with liquid. The reservoir 17 will be partially filled with liquid, at least to a level above the inlet passages or openings 16. The valve 4 will be closed rather than open as shown in Figure 1. When the transmitter plunger 1 is moved to the left, it will force fluid from the sub-chamber 13 through the transmission line 24 to the receiver, causing the receiver piston 26 to move to the left, compressing the spring 27. The spring 12 will cause the displacer 10 to follow the transmitter plunger 1, the valve 15 will remain closed, and the fluid in the chamber 11 will remain unchanged in volume as a fixed mass of fluid. Since the displacer 10 will move with but not relatively to the plunger 1, the displacer will not engage the cylinder 2. The returning of the transmitter plunger 1 will permit the receiver plunger 26 to move to the right to maintain pressure in the line 14 and chamber 13, and thus maintain the valve 4 closed. The displacer 10 will move together with the transmitter plunger 1 without changing its position relative to the plunger 1, and the valve 15 will remain closed. Hence, the body of fluid in the chamber 11 will remain constant.

Should fluid become lost, as by leakage from the transmission, the pressure in the line 24 and sub-chamber 13 will be maintained by the spring 12 which will move the displacer 10 toward the left relatively to the transmitter plunger 1, thereby discharging some fluid from the chamber 11 past the valve 4 into the sub-chamber 13, until pressure has been built up in the sub-chamber 13 to such a value as to cause the valve 4 to close. Consequently, the volume of fluid in the chamber 11 will be reduced, and the displacer 10 will be in a position on the transmitter plunger 1 more to the left than as shown in Figure 1.

5

This action will continue as loss of fluid continues until the left end of the displacer 10 again engages the right end of the cylinder 2 so as to arrest leftward movement of the displacer 10 while the transmitter plunger 1 continues to move to the left. The relative separating movement of the displacer 10 and transmitter plunger 1 thus effected will increase the volume of the chamber 11 so as to open the valve 15 and permit fluid to enter the chamber 11 from the reservoir 17. In this way, the displacer 10 and transmitter plunger 1 will be restored to the relative positions shown in Figure 1 with the chamber 11 then completely filled with liquid.

During continuous or intermittent delivery of fluid under pressure from the receiver to an extraneous point, the relative movement between the displacer 10 and the transmitter plunger 1 will be caused intermittently to take place in the manner described above so as to maintain in the chamber 11 sufficient fluid to replenish the fluid delivered from the receiver to the extraneous point.

If the system comprising the chambers 11 and 13, the transmission line 24, and the receiver 25-26-27 should be completely empty of liquid, the displacer 10 will be held toward the left by the spring 12, so that the left end of the displacer will abut the right end of the cylinder 2. In order to fill the system with liquid and restore the displacer 10 and the plunger 1 to their normal relative operating positions shown in Figure 1, the bleed valve plug 21 is unscrewed to open the bleed valve 20, the plug 22 is unscrewed, and the transmitter plunger 1 is reciprocated. When the plunger moves to the left, the displacer 10 will remain stationary because of its engagement with the right end of the cylinder 2, and the increasing of the volume of the chamber 11 thereby effected will cause the valve 15 to open so as to permit fluid to flow from the reservoir 17 into the space 11. Air contained in the sub-chamber 13 will be forced out through the transmission line 24, past the receiver 25-26-27, through the bleed line 19, past the bleed valve 20, through the opening 23, and the opening then uncovered by removal of the plug 22. On the rightward movement of the plunger 1, the spring 12 will, for a time, hold the displacer 10 stationary thereby causing a decrease in the volume of the chamber 11 and a discharge of fluid from this chamber past the valve 4 into the sub-chamber 13 and thence into the transmission line 24. When the plunger 1 again moves toward the left, more fluid will be taken into the chamber 11 through the valve 15, and on the next rightward stroke of the plunger fluid will be discharged into the sub-chamber 13 and thence into the transmission line 24. Repeated operations of this kind ultimately will cause the chamber 11, the sub-chamber 13, the receiver, and the bleed line to be filled with liquid. The bleed valve 20 may then be closed, the plug 22 replaced, and the apparatus operated in the normal manner previously described.

What I claim is:

1. An hydraulic transmitter comprising a cylinder, a plunger in the cylinder connected at one end of said cylinder to a transmission pipe line, a displacer forming conjointly with said plunger and the other end of the cylinder a liquid-receiving chamber, the plunger having an opening for connecting the said one end of

6

the cylinder to the liquid receiving chamber, a reservoir for liquid, the displacer having an opening for connecting the said chamber to the reservoir, means to reciprocate the plunger, spring means so connecting the plunger and the displacer that transmission movement of the plunger tends to move the displacer with it, means to limit such movement of the displacer, a non-return valve to close the opening in the plunger when the plunger is moved on its transmission stroke and a non-return valve to close the opening in the displacer when the plunger moves on its return stroke.

2. An hydraulic transmitter comprising a cylinder open for connection to an hydraulic transmission pipe line, a hollow plunger, a hollow displacer slideable on the plunger, the plunger and displacer defining a chamber between them, means to move the plunger on its transmission stroke, means resiliently connecting the plunger to the displacer so that transmission movement of the plunger tends to move the displacer with it, a passage in the plunger connecting the chamber to the transmission connection of the cylinder, a non-return valve in said plunger to close the passage when the plunger moves on its transmission stroke, a reservoir for liquid, a passage in the hollow displacer to connect the chamber to the reservoir, and a non-return valve to close the passage in the displacer when the plunger moves on its return stroke.

3. An hydraulic transmitter comprising a transmission pipe line connection, a liquid reservoir, a chamber, a pump having a movable pumping element interposed between said transmission pipe line connection and said chamber, a displacer interposed between said chamber and said liquid reservoir, spring means so connecting the pumping element and the displacer to one another that pumping movement of the pumping element tends to move the displacer with it, means to limit such movement of the displacer, the pumping element having a through opening for providing communication between said pipe line connection and said chamber and the displacer element having a through opening for providing communication between said chamber and said reservoir, valve means to close the opening in the pumping element when that element moves on its transmission stroke, and valve means to close the opening in the displacer element when the pumping element moves on its return stroke.

55 4. An hydraulic transmitter as claimed in claim 3, and having also a connection for a bleed line, the said connection having a valve to open the connection to the reservoir.

60 PERCIVAL EDWARD THOMAS.
